UNITED STATES PATENT OFFICE.

LEMUEL E. VAN TREESE, OF LETTS, INDIANA.

PNEUMATIC HORSE-COLLAR.

1,206,624.

Specification of Letters Patent. Patented Nov. 28, 1916.

Application filed March 29, 1916. Serial No. 87,536.

To all whom it may concern:

Be it known that I, LEMUEL E. VAN TREESE, a citizen of the United States, residing at Letts, in the county of Decatur and 5 State of Indiana, have invented new and useful Improvements in Pneumatic Horse-Collars, of which the following is a specification.

The present invention relates to horse collars, and more particularly to pneumatic horse collars.

The primary object of the invention is the provision of a device of the above stated character, which is simple in construction, 15 durable in use, and may be manufactured at comparatively low cost, and wherein the pads of the collar by being inflated, will serve in protecting the shoulders of the animal from injury when the collar is subjected to undue strains.

A further object of the invention is the provision of side members forming the collar, and each provided with flanges adapted 25 to clench the beaded side edges of the collar pads and thereby retain the latter upon the side sections of the collar, and a covering for the pads is also provided to prevent the loss of the pads from the collar sections, and further present the collar with a neat and 30 finished appearance at all times.

With the above and other objects in view, the invention consists in the novel features, details of construction, and combination of parts which will hereinafter be more fully 35 set forth, illustrated in the accompanying drawing, and pointed out in the appended claims.

Figure 1 is a front elevation of the collar; Fig. 2 is a transverse section taken through 40 one of the side sections and pads of the collar; and Fig. 3 is a side view of the collar illustrating the manner of securing the covering to one of the clamping flanges.

Referring more particularly to the accompanying drawings, in which like characters of reference refer to corresponding parts in the several views. A denotes my improved horse collar, constructed of a pair of side sections 5 and 6 respectively. Each of these 45 side sections constitutes a metal plate 7, formed on the front face thereof and along one of the side edges with a rib or hame support 8. This plate 7 is formed along the opposite side edges thereof with rearwardly 50 projecting and inwardly bent clamping hooks 9 and 10 respectively. In carrying

out the invention, it is my object to employ a pair of yieldable pads 11 and 12 respectively. The said pads are identical in construction, and each includes a split casing 13, formed 60 with reinforced or thickened ends 14 formed with exterior grooves 15, in which the in-turned hooked ends engage, and thereby clamping the pads upon the respective side sections 5 and 6 of the collar. Mounted 65 within the split casing 13, is an inflatable tube 16, having valves 17 which protrude through the casing 13 at points adjacent the lower bottom edge or throat portion of the collar. 70

The sections 5 and 6 are hingedly connected together at their upper edges through the medium of the flexible connection or hinge 18, while the collar is fastened in applied position upon the neck of the animal 75 by means of the clasp 19. This clasp 19 is constructed by extending the lower ends of the respective side sections beyond the lower terminals of the beadings 8, and are adapted to overlap one another, that is to say, the 80 uppermost end of the fastening device is provided with a staple 20 adapted to protrude through a slot 21 formed in the lowermost plate of the fastening device, and protrudes beyond the plane of the same a 85 sufficient distance to permit of the insertion of the hame fastening straps therethrough. A protecting plate 22 is fixedly secured at one end to the side section 5 of the collar, and is adapted to underlie the points of the 90 hinge connection 18 to prevent injuring the neck of the animal when the collar is in applied position.

Riveted or otherwise suitably secured at one terminal to the flange 9 is a covering 23 95 constructed preferably of leather, and is adapted to be brought over the facing of the casing, as better shown in Fig. 2 of the drawing. The free vertical edge of the covering 23 is formed with a series of eyelets 24. The flange 15 has formed on the exterior face thereof, an extension 25 formed with a series of vertically aligned openings 26. A lacing cord or other suitable means 27 is adapted to pass through 100 the eyelets 24 of the covering, and the opening 26 of the protection, for fastening the covering in applied position.

From the foregoing description, taken in connection with the accompanying drawing, 110 the advantages of construction, and of the method of operation will be readily appar-

ent to those skilled in the art to which the invention relates, and while I have described the principles of operation of the invention, together with the device which I now consider to be the best embodiment thereof, I desire to have it understood that the device shown is merely illustrative, and that such advantages may be made when desired as are within the scope of the claims appended thereto.

I claim:

1. In a horse collar, side sections hingedly connected together at their upper ends, each of said side sections being formed with clamping flanges, one of said clamping flanges being provided with a perforated projection, a cushioning pad fastened on each of said side sections through the medium of said flanges, a covering for said cushioning pad fixed at one end to the other of said clamping flanges and provided with a series of eyelets in the free edge thereof, and means passing through the openings of said projections and through the eyelets of

the covering for fastening the latter over 25 the pads and to the said projection.

2. In a horse collar, hingedly connected side sections, each formed with inturned clamping flanges, one of said flanges being formed with a projection having a series of 30 openings, a split casing formed with thickened grooved edges, the grooves of the casing receiving the inturned clamping flanges of said side sections for clamping the casing thereon, a tubing in said casing, a covering for said casing fastened at one end to one of said inturned flanges and detachably connected with the projection of the other of said inturned flanges, and means for fastening the lower ends of the fastening members together.

In testimony whereof I affix my signature in presence of two witnesses

LEMUEL E. VAN TREESE.
